PUMP AND VALVE ASSEMBLY

William C. Anthony and Glenn S. Park, Streator,
Ill.; said Park assignor to said Anthony

Application May 7, 1951, Serial No. 224,853

20 Claims. (Cl. 103—41)

1

This invention relates to a pump and has for one object to provide a pump and pump control.

It has for another object to provide controlling means which may be associated with a pump, which controlling means may be readily operated from the outside of the pump.

Another object is to provide a rotating valve in connection with a pump which may be readily operated from a point external from the valve housing.

Another object is to provide a controlling valve in connection with a gear pump and to provide a valve so arranged that it is substantially balanced and may be freely and readily operated.

Other objects will appear from time to time throughout the specification and claims.

The invention is illustrated more or less diagrammatically in the accompanying drawings, wherein:

Figure 1 is a sectional view through the pump illustrating parts in section and parts in elevation;

Figure 2 is a longitudinal section taken at line 2—2 of Figure 1;

Figure 3 is an elevation of the valve operating member removed from the pump housing and associated parts;

Figure 4 is a transverse sectional view taken at line 4—4 of Figure 1;

Figure 5 is an outside end elevation in a reduced scale;

Figure 6 is a sectional detail taken on line 6—6 of Figure 2;

Figure 7 is a sectional detail taken at line 7—7 of Figure 2;

Figure 8 is a similar view showing the valve in a different position of adjustment; and

Figure 9 is a front view of the inner pump housing member.

Figure 10 is a sectional view showing a modification of the device in which the valve assembly, although generally similar to that shown in the earlier figures, is contained in a housing separate from the pump;

Figure 11 is a section taken at line 11—11 of Figure 10;

Figure 12 is a transverse section taken at line 12—12 of Figure 10; and

Figure 13 is a diagrammatic plan view showing the separate valve housing in circuit in a system which includes a pump.

Figure 14 is a sectional detail, on a reduced scale, showing a modified form of pump shaft construction.

Like parts are indicated by like characters throughout the specification and the drawings.

2

The pump comprises a housing, a pair of meshing gears, a valve assembly and valve operating means. The housing includes generally a central or inner member in which the gears are positioned, and two side plates which close the housing and which, with the central member, form the full pump housing. 1 is a central or inner pump housing member. As shown in Figures 2 and 9, this member is shaped to provide two main gear retaining cavities 2 and 3. It is shaped also to provide an inlet or low-pressure passage 4 and an outlet or high-pressure passage 5. It may be widened as at 6 to provide a plate-like extension by means of which the pump may be attached and, if desired, it may be provided, intermediate that part which contains the gears and the enlargement 6, with a reduced portion 7 within which the controlling valve is located.

The passage 8 is formed between the inlet passage 4 and the outlet passage 5. One side of the housing 1 is closed by a cover plate or comparable member 9, which may be enlarged at 10, and is generally held removably in place upon the member 1 by screws 11 or otherwise. The member 9 is provided with cavities suitable to receive the shafts or other members upon which the gears are supported.

Within the member 1, as above mentioned, is a cavity adapted to receive and support a combined check and relief valve and the controls therefor. 20 This valve includes a cage 12 positioned within the upper or discharge outlet of the upper or high-pressure passage 5. As shown, the cage is provided with an inwardly bent lower or inner end 13 which forms a seat for a ball 14. A spring 15 bears at one end against the ball and at the other on a pin 16 which extends across the cage. The spring is biased to hold the ball seated.

Positioned within the passage 8, which extends from the intake or low-pressure side 4 to the high-pressure side 5 of the pump housing, is a valve member 17. This is a generally flat member and it is shaped as shown particularly in Figures 7 and 8 with two perforations or openings 18, 18 formed through it.

A valve and a valve shifting member are positioned in line with the spaces or perforations 18 and in line with the valve member 17. The valve member itself is of butterfly shape, as shown particularly in Figures 6 and 8, and comprises two oppositely placed segmental valve members 19, 19 which are of equal size and are preferably integral with the valve shifter shaft 20. This shaft is provided with an enlarged bearing portion 21 positioned intermediate its ends, and with a reduced and flattened or cut-away part 22.

Positioned opposite the part 22 is a raised rounded portion 23 which is concentric with the shaft 20 and with the axis of rotation of the valve portions 19.

As shown in Figure 2, the valve portions 19 are positioned in contact with the valve member 17 and in contact with the surface of the perforation or opening 18. The bearing portion 21 of the shaft 20 is received in a bearing 24 fixed in an opening in the housing portion 1. Suitable sealing members 25 and 26 are positioned to seal the bearing or bushing 24. The member 25 is in contact with the housing 1 and the member 26 is in contact with the bearing portion 21. Sealing means of any desirable type may be provided exteriorly of the bearing portion 21. As shown in Figure 2, these means comprise a number of packing glands, washers and the like, designated generally by the numeral 27. The invention is obviously not limited to any particular sealing means in this respect.

An operating lever or handle 28 is positioned upon the outer or free end of the shaft 20 and may be secured thereto by a pin 29 or otherwise. A second cover plate 30 is positioned on the opposite side of the pump housing by screws 31 or otherwise, and this cover plate is perforated to permit the passage of a driving shaft.

As shown in detail in Figure 1, a driving shaft 32 passes through a portion 33 of the cover plate 30 and is fixed to a gear 34. An anti-friction bearing 35 is positioned about shaft 32 with any suitable cavity 36 formed within the cover plate 30. Packing and equivalent means 37 are positioned about the shaft 32 within a cavity 38 formed in line with and exteriorly of the cavity 36. At its opposite end, the shaft 32 is received in a suitable bearing formed in the cover plate 9. This construction is indicated diagrammatically at 39 in Figure 1. The invention is, of course, not limited to the particular details of bearings or bearing supporting means, and any suitable gear construction and gear journaling and driving means may be used without departing from the spirit of the invention.

A second gear 40 is in mesh with the gear 34 and is carried on a shaft 41 which, at one end, is supported in a suitable bearing carried by the cover plate 9 and, at the opposite end, is supported in a suitable bearing covered by the cover plate 30.

Preferably integral with the cover plate 30, there is formed a pressure relief assembly. This includes, as shown generally in Figures 1 and 4, a passage 42 in communication with the inlet or suction chamber 4 of the pump housing, and a second passage 43 in communication with the outlet or high-pressure passage 5 of the pump housing. The pump housing member is suitably ported at 44 and 45 to provide communication between the passages 42 and 44, respectively, and the passages 43 and 45, respectively. The outer or discharge end of the passage 43 is tapered or otherwise shaped as at 46 to provide a seat for a ball-check valve 47.

A piston 48 is positioned to bear against the ball 47 and to control the flow of fluid from the passage 43 into the passage 42. This piston 48 is held in contact with the ball 47 and the latter is normally held closed by a spring 49 which bears at one end against the inner face of the bypass piston 48 and, at the other end, bears against the adjustable plug 50. This plug is threaded and is adjustably received in a corresponding threaded opening in the extension 51, which is

preferably integral with the cover plate 30. The bypass valve 48 may be exteriorly grooved or cut away as at 52 and a perforation or passage 53 passes from the cut-away portion 52 to the interior of the valve member 48.

To permit a rearrangement of the relative position of the pump housing and the cover plates to compensate for a difference in the direction of rotation of a power take-off or other drive, certain passages and ducts, additional to those above described and corresponding to them, are present, both in the pump housing 1 and the cover plate 30. In Figure 4, the passages 42 and 43 appear in full lines and are connected to passages 44 and 45, respectively, which are in communication with the low pressure side 4 and the high-pressure side 5 of the housing. For certain purposes which will be described more fully below, it is desirable to reverse the cover plates from the position shown in Figures 1 and 4. When that reversal is made, the cover plate 9 is positioned on the left side of the pump housing 1 and the cover plate 30 is positioned on the right side of the pump housing 1. The use of the words, "right," and "left," in the sentence just above applies to the showing of the device as they appear in Figures 2 and 4.

To permit this reversal of cover plates and to insure the proper connection of the pressure relief assembly with the high- and low-pressure sides of the pump, a branch 42¹ is connected to the passage 42 and inclined downwardly. It enters or is in communication with the passage 42 through an opening 42². Similarly an inclined branch 43¹ is positioned generally below the plane of the passage 43. It is in communication with the passage 43 through the opening 43².

Communicating respectively with the high- and low-pressure sides 4 and 5 of the pump housing 1 are passages 44¹ and 45¹. These members or passages are positioned, as shown in Figure 9, below the corresponding passages 44 and 45.

When the parts are assembled as shown in Figure 4, the branch passages 42¹ and 43¹ are inactive. They are below the passages 44 and 45 and are sealed off. When the parts are reversed so that the cover plate 30 is on the right-hand side of the housing 1 and the cover plate 9 is on the left-hand side of the housing 1, the passages 44 and 45 are sealed by the cover plate 9 and the outer ends of the passages 42 and 43 are sealed by their contact with an imperforate portion of the pump housing. The branch passages 42¹ and 43¹ are then in communication with the passages or openings 44¹ and 45¹ of the pump housing 1. Thus, whether the cover plate 30 be on the left-hand side of the pump housing 1 as shown in Figure 4, or be reversed and attached to the right-hand side of the housing 1, the passage 42 is always in communication with the low-pressure side 4 of the housing and the passage 43 is always in communication with the high-pressure side 5 of the pump to permit pressure relief when necessary by movement of the ball 47 away from the seat 46 and by movement of the valve 48 out of the position shown in Figure 4, in which it blocks the flow of fluid in the outlet direction from the passage 43 to the passage 42.

Generally speaking, the valve assembly as shown in Figures 10 to 13, inclusive, comprises the same control valve shown in the earlier figures. In the earlier figures, the control valve is mounted in a suitable cavity or chamber formed in the pump housing, and the other valve is also positioned in a cavity formed in the pump hous-

ing. In the form of Figures 10 to 13, these valves operate as they do in the earlier form. They are, however, merely enclosed in a separate housing which may be any place in the pump system.

49 is a housing provided with a passage 50 through it. This passage is threaded at each end, as at 51 and 52. Conduits 53 and 54 are positioned, respectively, in the threaded portions 51 and 52. The conduit 54 may be connected to a pump housing 55. The flow of liquid to the pump will be generally in the direction of the arrow shown in the conduits 53 and 54. A second conduit 56 is connected with the pump 55 and comprises an outlet or high pressure path. The conduit 56 is connected to a threaded opening 57 formed in the valve housing 49. A conduit 58 is connected to the housing 49 and comprises the outlet conduit or path for high pressure fluid. The direction of flow of the high pressure fluid is indicated by the arrows on the conduits 56 and 58, as shown in Figure 13.

The valve housing 49 thus contains a low pressure chamber or passage 50 and a high pressure chamber or passage 59. Between these chambers is a passage 60 which may be closed. This passage 60 is comparable to the passage 8 as shown in Figure 2 and is closed by a valve which is identical with the valve 19 of the earlier figures. Since this control valve is identical in both forms of the invention, the same reference numerals are applied to it in both forms and it is not re-described herewith. Ordinarily, this valve is interchangeable so that it may be applied to a device as shown in Figure 2 in which the valve is assembled in the same housing as that in which the pump is positioned or to a device in which the pump is in one housing and the valve in another, as shown in Figures 10 to 13, inclusive. The valve, the sealing means and the valve operating means are all the same in all forms of the figures. The opening or passage 60 is partially closed by a plate 61 which is provided with a plurality of perforations or openings 62. The plate corresponds to the plate 17 of Figure 2 and the openings 62, 62 correspond to the openings 18 of Figures 7 and 8, in particular.

Positioned also within the housing 49 is an outlet ball check valve identical with the outlet ball check valve shown in Figure 2. Since the parts are identical and their function is identical, they are interchangeable and the same reference numerals are applied to the same parts in both figures and they are not redescribed herewith. The cage 12 is positioned in the outlet or high pressure passage of the housing 49 with which the conduit 58 is in communication.

Where the control valve is mounted in a separate housing, a pressure relief system may be applied, and it is generally the same as that shown in the earlier figures. It comprises a ball check valve 63 positioned to be seated in a tapered seat 64 which communicates with a passage 65. The passage 65 is in communication with the high pressure chamber 59. The tapered seat 64 comprises an enlargement of the passage 65 and the tapered portion communicates with a cylindrical cavity 66 within which is positioned a piston-like member 67. The ball 63 bears against the closed end of the member 67, and a spring 68 is positioned within the member 67 and bears at one end against the closed part of that member, and at the other end bears against an adjustably positioned closing plug 69, which latter is received in a threaded seat 70 formed in a suitable portion or extension of the housing 49. A

peripheral groove 71 may be formed in the member 67 and may be provided with a perforation 72 communicating with the interior of the member 67. A passage 73 communicates with the cylindrical chamber 66 and finally communicates with the low pressure chamber 50. This pressure relief assembly, including the ball check valve 63 and the member 67, is substantially the same as the corresponding members shown in the earlier figures, such as the ball 47, the piston 48 and the passages which lead to the chamber in which the piston is positioned.

Although we have shown an operative form of our invention, it will be recognized that many changes in the form, shape and arrangement of parts can be made without departing from the spirit of the invention, and our showing is therefore to be taken as, in a sense, diagrammatic.

The use and operation of this invention are as follows:

With the parts assembled as shown, the pump will be positioned on a base or support of any suitable construction and will be associated with driving means. Frequently a pump of the type disclosed will be positioned on an automotive vehicle where hydraulically actuated equipment is present. This may include tipping or elevating devices actuated by hydraulic piston and cylinder assemblies. If that is the case, the pump will be connected to such a device and will normally be operated by the engine of the vehicle. This type of use and association is mentioned merely as being typical of one use for which the pump of the present invention is adapted.

It is adapted also for many other uses. However used, it will be connected to a mechanism intended to be operated by hydraulic fluid under pressure and the shaft 32 will be driven. With the shaft being driven in the direction of the arrow of Figure 2, the gear 34, of course, rotates with it, and the gear 40 in mesh with the gear 34 rotates in the opposite direction, as indicated by the arrow on the shaft 41. Fluid is thus carried by the gears from the low-pressure side 4 to the high-pressure side 5. For normal operation, the valve member 19 will be closed in the position of Figure 7. As pressure builds up on the high-pressure side, it will displace the ball 14 against the resistance of the spring 15 and high-pressure fluid will be discharged through the cage 12 and to the point of use. When for any reason pressure on the high pressure side falls sufficiently, the ball 14 will be reseated by the spring 15.

Pressure relief means are also provided in the system. One purpose of a pressure relief means is to prevent the development of excessive pressures. The structure illustrated in plan in Figure 4, and shown also in Figure 1, is concerned primarily with the pressure relief mechanism. The cover plate 30 contains the passages 42 and 43. These passages, by means of one or the other of the passages 44 and 45, are connected respectively with the low-pressure chamber or side 4 of the pump and the high-pressure chamber or side 5.

The plug 50 is adjusted to give the desired pressure to the spring 49. Obviously, springs of various sizes might be used and, in that event, the adjustment is accomplished by selecting the proper spring rather than by adjusting the plug 50. In either event however, the parts are chosen or adjusted to apply, to the plunger 48, the right degree of resistance to movement in the outward direction. The plunger in the closed position,

as shown in Figure 4, closes the passage 42 and bears against the ball 41. Upon the occurrence of pressure above a predetermined maximum in the high-pressure side 5, the ball check valve 47 will be moved outwardly from the seat 46 and will move the plug 48 against resistance of the spring 49 and, thus, the passage 43 is opened and high-pressure fluid may be bypassed through the passage 43 and the passage 42 to the low-pressure side 4 of the pump.

As long as power is thereafter applied to the pump, it may continue to generate the maximum pressure and the bypass may remain open. This operation would be satisfactory for relatively short periods with the ball alone but, should it be necessary to continue pump operation at speeds sufficient to generate the maximum pressure, excessive heating of the fluid within the pump may develop. For this reason, the plunger type valve 48 is necessary. The plunger or trunk type valve, in addition to the ball valve, comprises a differential piston. It is to be understood that the plunger 48 might be omitted and the spring 49 shaped to bear directly upon the ball 41. In that case, the pressure relief valve would be a simple or conventional ball check relief valve. The addition to the ball valve of the plunger 48 produces a differential piston action. The ball comprises a primary valve and is held against its seat by the compression of the spring. The area of the ball exposed to pressure within the passage 43 is considerably less than the cross sectional area of the cavity within the valve 48 is positioned. If the spring be so proportioned that the ball will be lifted from its seat at a predetermined pressure of 12 pounds per square inch, it will be found that, after it has been lifted by this pressure, the pressure flows around the displaced ball and contacts the secondary valve member, the plunger 48. This piston or plunger valve is moved outwardly against the compression of the spring 49 and, because its exposed area is several times greater than that of the ball on the seat opening, the plunger will be held open by a pressure which is substantially less than that required to open the ball. Thus, the pump may continue to operate and to run at almost idling speed and, after the valve 48 has once been unseated by pressure, the pressure will continue to be relieved without the necessity of high-pressure generation, and the pump may operate at very low pressure.

A main controlling means comprises the valve assembly shown generally in Figure 2, and illustrated in part in Figures 6, 7 and 8. When the valve operating means are in the position of Figure 2, which is the position for delivery of fluid, under pressure, outwardly through the valve cage 12 the projection 23 is out of contact with the ball 14 and the position of the projection 23 is thus different from that which it occupies in Figure 6, which is the position for the return of fluid inwardly through the valve cage 12. In Figure 2, the ball, to some degree, projects within the flattened or cut-away portion 22 of the shaft 20. This is the position, also shown in Figure 7, in which the valve parts 19 wholly cover the ports or openings 18 and, thus, completely block the passage 8 and prevent the bypassing of pressure fluid from the high-pressure side to the low-pressure side of the pump.

If now it becomes desirable to permit bypassing of fluid from the high-pressure side to the low-pressure side, the shaft 20 is rotated by the handle 28. A slight movement from the position

of Figure 7 will partially open the ports 18 and a considerable movement in the opening direction may occur before the enlargement 23 contacts the ball. Thus, the first movement of the shaft 20 from the position of Figure 2 toward that of Figure 6 will open or uncover the ports 18 to some degree without contacting the ball. Ordinarily, the ball itself will be raised from its seat by pressure on the high-pressure side at the time when the valve 19 is to be moved to uncover the ports. The only time when this is not the case is when the pump has stopped operation or is not operating at maximum speed and it is desirable to open the ball 14 to permit fluid to return to the pump from a cylinder or other mechanism into which it has been previously forced.

In any event, as the movement of the shaft 20 is continued to bring the projection or raised portion 23 from the downward position of Figure 2 to the upper position of Figure 6, the member 23 presently comes in contact with the ball 14 and raises it from its seat. As shown in Figure 6, the ball is fully raised from its seat. Since the ball contacting surface of the member 23 is arcuate and is concentric with the axis of rotation of the shaft 20, the ball will be fully raised from the seat for many positions of adjustment of the shaft 20. It is possible, by adjusting the shaft, to raise the ball 14 from its seat fully, as shown in Figure 6, when the ports 18 are closed and, by a different adjustment of the shaft 20, it is possible to raise and hold the ball 14 out of contact with the seat when the ports 18 are wholly or partially uncovered. The member 23, as shown in Figure 6, projects into the cage 12. This is due to the fact that this member is of greater diameter than the shaft portion 20 or the enlarged portion 21. It projects outwardly beyond either of these, and, thus, it projects into the cage and accomplishes a greater raising of the ball 14 than would be possible if its diameter were less.

The device includes the pump and the valve assembly. They may be together in a single housing, as shown, or they may be in separate housings, as shown. The control valve and the automatic bypass valve are shown as present in both forms of the device. The automatic bypass valve may, however, be omitted, if desired, from either form of the device. The operation of the control valve is distinct from the operation or presence of the automatic bypass valve.

The operation thus far described applies to the parts when assembled as shown. Since, as above noted, the device finds one important use as a driving means for hydraulic mechanisms carried by trucks or other automotive vehicles, it will frequently be driven through the power take-off of the vehicle engine. Such power take-offs in some mechanism of vehicles rotate in one direction and, in other mechanisms, rotate in the opposite direction, and means are provided in the structure of the present invention to permit operation of the pump by rotation in either direction. The low-pressure side 4 of the pump is always the low-pressure side, and the high-pressure side 5 of the pump is always the high-pressure side. With the parts as shown, rotation of the driving shaft 32 is in counter-clockwise direction, and it may be assumed that the power take-off drive connected to this shaft is in counter-clockwise direction. If the power take-off drive be in clockwise direction, some adjustment must be made to permit the rotation

of the gears in proper direction to discharge the fluid under pressure into the high-pressure side 5. This may be accomplished in a number of ways. The one shown is as follows:

The cover plates 9 and 30 are removed from the pump and the pump body is rotated through 180 degrees and the cover plates are then re-attached to the pump body. This is, in effect, to reverse the cover plates from the positions shown in Figures 1 and 4 so that the cover plate 9 lies on the left-hand side of the pump housing 1 and the cover plate 30 lies on the right-hand side of the housing 1. In that position, the passages 42 and 43 are blocked at their outer ends by the cover plate 9 or the gasket positioned between it and the housing 1. This also closes or blocks the passages 44 and 45. However, the branch passages 42¹ and 43¹ are thus brought into communication, respectively, with the passages 44¹ and 45¹, and this rearrangement of the parts still provides a system of passages through which high-pressure fluid from the high-pressure side 5 reaches the ball valve 47 and, if the pressure is sufficient to raise that valve and the plunger type valve 48, high-pressure fluid will be bypassed through the branch 43¹, the valves 47 and 48, and finally through the branch 42¹ into the low-pressure side 4. Thus, means are provided to permit the relative arrangement of the pump housing and cover plates so that, without the addition or substitution of any parts, that arrangement may be selected which provides a proper adjustment to permit driving of the pump from a power take-off or other driving means which operates either counter-clockwise or clockwise.

Another means of accomplishing this result is to build the pump with both of the gear shafts 32 and 41 extending from the pump body. Either shaft may be driven, according to the rotation of the power takeoff shaft, reversal being then merely a matter of selection of the shaft to be driven, as shown in Figure 14.

The valve system illustrated in the modified form of Figures 10 to 13, inclusive, is substantially the same as that shown in the earlier figures in which the valves are positioned within the pump housing instead of being positioned within a separate valve housing. The rotary valve member, including the portions 19 to 23, inclusive, are identical in both forms of the invention, and their operation is identical and need not be redescribed. The pressure relief valve system comprising the ball 63 and the piston 67 are the same as those described above in connection with the earlier figures. When pressure on the high-pressure side of the system becomes sufficient, the ball 63 is unseated by that pressure, and when it has been unseated, the closed end of the piston 67 is unseated, and this, having a greater area exposed to the high pressure than would the ball 63, will be held open with a pressure less than that required initially to move the ball 63 to the open position. Once the ball 63 and piston 67 have been opened, pressure is relieved through the passage 65, past the seat 64 and through the cylindrical cavity 66 and finally through the passage 73. So long as the pressure on the high-pressure side of the system remains sufficiently high to hold the piston valve 67 open, pressure is relieved from the high-pressure side to the low-pressure side of the system.

The valve assembly in the separate housing may be positioned anywhere in the system which

will normally include a pump, a member to be operated by fluid pressure and the necessary conduits. The member operated by the fluid pressure will frequently comprise a piston and cylinder assembly, and these are not shown here-with as the invention is not limited to any particular design of piston and cylinder assembly.

In the modified form of Figure 14, both gear shafts 32 and 41 extend outwardly from the pump body. To permit this, the cover plate 74 is substituted for the cover plate 30, and two passages are provided through members 75 and 76 for the shafts 32 and 41 respectively. The same bearing and packing means, as shown in Figure 1 and described in connection with that figure, are also used in connection with the form of Figure 14. For that reason these parts will not be re-described in connection with that figure. The purpose of the construction of Figure 14, as pointed out above, is to provide two shafts, each extending outwardly from the pump casing, and each of which may be driven by the power take-off shaft. If one shaft is driven the pump will operate in one direction, and if the other shaft is driven the pump will operate in the opposite direction. Thus, by the use of a selected shaft, the pump may be driven from a previously installed power take-off to operate either clockwise or counterclockwise.

We claim:

1. In combination in a housing member, said housing member shaped to define a low and a high pressure passage, a ball check valve positioned to control the passage of high pressure fluid outwardly through said high pressure passage, said housing being shaped to provide a communication between said high and said low pressure passages, said communication including a plurality of openings, a rotary valve member positioned to control said openings, a shaft for said rotary valve member, a part on said shaft adapted in one position to raise said ball check valve from its seat, and spring means biased to hold said rotary valve member in contact with the member in which said openings are formed.

2. In combination in a housing member, said housing member shaped to define a low and a high pressure passage, a ball check valve positioned to control the passage of high pressure fluid outwardly through said high pressure passage, said housing being shaped to provide a communication between said high and said low pressure passages, said communication including a plurality of openings, a rotary valve member positioned to control said openings, a shaft for said rotary valve member, a part on said shaft adapted in one position to raise said ball check valve from its seat and to penetrate inwardly beyond its seat, and spring means biased to hold said rotary valve member in contact with the member in which said openings are formed.

3. In combination, a housing member, said housing member shaped to define a low and a high pressure passage, a ball check valve positioned to control the passage of high pressure fluid outwardly through said high pressure passage, a seat for said check valve, said housing being shaped to provide a communication between said high and low pressure passages, said communication including a plurality of openings, a rotary valve member positioned to control said openings, a shaft for said rotary valve member, a part on said shaft adapted in one position to extend inwardly beyond said check

valve seat and to raise said ball check valve from its seat, means adapted to hold said rotary valve member in contact with the member in which said openings are formed, a passage joining said high and low pressure passages, a plurality of valve member positioned in said passage, said last mentioned valve members comprising a ball, a spring member and a plunger, said plunger being normally in contact with said ball and said spring member being effective to urge said plunger and said ball to passage closing position.

4. In combination, a housing member, a low and a high pressure passage through said housing, a ball check valve positioned in said high pressure passage, a seat therefor, a second passage leading from said high pressure passage to said low pressure passage, a member positioned in said second passage being provided with a plurality of openings, a valve positioned adjacent said member to close said openings, a shaft for rotating said valve to move it to open or closed position, and a part on said shaft adapted, when suitably positioned, to contact said first mentioned ball check valve, to extend inwardly beyond its seat and to move said valve in the opening direction.

5. In combination in a pump, a housing member shaped to provide a pumping chamber and fluid ducts, a pair of meshing gears positioned therein, an inlet and an outlet passage communicating with said pump chamber, a pair of cover plates adapted to be attached to and to close said housing, a bypass valve positioned to bypass fluid from the high pressure side to the low pressure side of said pump, said bypass including a fixed ported member, a rotary shaft, a valve member carried by said shaft in contact with said ported member at all positions of rotation of said shaft, and means for adjusting said shaft to adjust said second valve member into desired position.

6. In combination in a pump, a housing member shaped to provide a pumping chamber and fluid ducts, a pair of meshing gears positioned therein, an inlet and an outlet passage communicating with said pump chamber, a pair of cover plates adapted to be attached to and adapted to close said housing, a bypass positioned to bypass fluid from the high pressure side to the low pressure side of said pump, said bypass including a fixed ported member having a flat face, a rotary shaft, a valve member having a flat face and carried by said shaft in contact with the flat face of said ported member at all positions of rotation of said shaft, and means for adjusting said shaft to adjust said second valve member into desired position.

7. In combination in a pump, a housing member shaped to provide a pumping chamber and fluid ducts, a pair of meshing gears positioned therein, an inlet and an outlet passage communicating with said pump chamber, a pair of cover plates adapted to be attached to and adapted to close said housing, a bypass valve positioned to bypass fluid from the high pressure side to the low pressure side of said pump, said bypass including a fixed ported member, a rotary shaft, a valve member carried by said shaft in contact with said ported member, means for adjusting said shaft to adjust said second valve member into desired position, and a ball check valve positioned on the pressure side of said pump housing, said rotary valve adjusting means provided with a part to contact said ball in a suitable position of adjustment to raise the same.

8. In combination in a pump, a housing member shaped to provide a pumping chamber and fluid ducts, a pair of meshing gears positioned therein, an inlet and an outlet passage communicating with said pump chamber, a pair of cover plates adapted to be attached to and adapted to close said housing, a pressure relief passage formed in one of said closure plates, said pressure relief passage formed in said cover plate being so disposed that it will communicate with the same fluid ducts when fastened to either side of the pump housing, a bypass valve positioned to bypass fluid from the high pressure side to the low pressure side of said pump, said bypass including a fixed ported member, a rotary shaft, a valve member carried by said shaft in contact with said ported member, means for adjusting said shaft to adjust said second valve member into desired position, and a ball check valve positioned on the pressure side of said pump housing, said rotary valve adjusting means provided with a part to contact said ball in a suitable position of adjustment to raise the same.

9. In combination in a pump, a main housing member, said housing member shaped to define a pumping chamber, a low and high pressure passage communicating with said pump chamber, a ball check valve positioned to control the passage of high pressure fluid outwardly through said high pressure passage, said pump housing being shaped to provide a communication between said high and said low pressure passages, said communication including a plurality of openings, a rotary valve member positioned to control said openings, a shaft for said rotary valve member, a part on said shaft adapted in one position to raise said ball check valve from its seat, closure means for closing said housing member, a pair of meshing gears positioned in said pump chamber, shafts supporting said gears, and spring means biased to hold said rotary valve member in contact with the member in which said openings are formed.

10. In combination in a pump, a main housing member, said housing member shaped to define a pumping chamber, a low and a high pressure passage communicating with said pump chamber, a ball check valve positioned to control the passage of high pressure fluid outwardly through said high pressure passage, a seat for said check valve, said pump housing being shaped to provide a communication between said high and low pressure passages, said communication including a plurality of openings, a rotary valve member positioned to control said openings, a shaft for said rotary valve member, a part on said shaft adapted in one position to extend inwardly beyond said check valve seat and to raise said ball check valve from its seat, a pair of cover plates adapted to be positioned on said housing member, a pair of meshing gears positioned in said pump chamber, shafts supporting said gears, one of said shafts extending through a cover plate, means biased to hold said rotary valve member in contact with the member in which said openings are formed, a passage joining said high and low pressure passages, a plurality of valve members positioned in said passage, said last mentioned valve members comprising a ball, a spring member and a plunger, said plunger being normally in contact with said ball and said spring member being effective to urge said ball and plunger one toward the other to close said passage.

11. In combination in a pump, a main housing member, a plurality of cover plates adapted re-

movably to be positioned upon said housing member and forming with said housing member a pump chamber, a low and a high pressure passage to and from said chamber, a pair of meshing gears positioned within said pump chamber, a ball check valve positioned in said high pressure passage, a seat therefor, a second passage leading from said high pressure passage to said low pressure passage, a member positioned in said second passage being provided with a plurality of openings, a valve positioned adjacent said member to close said openings, a shaft for rotating said valve to move it to open or closed position, and a part on said shaft adapted, when suitably positioned, to contact said first mentioned ball check valve, to extend inwardly beyond its seat and to move said valve in the opening direction.

12. In combination in a pump, a main housing member, said housing member shaped to define a pumping chamber, a low and a high pressure passage communicating with said pump chamber, said pump housing being shaped to provide a communication between said high and low pressure passages, said communication including a plurality of openings, a rotary valve member positioned to control said openings, a shaft for said rotary valve member, closure means closing said housing member, a pair of meshing gears positioned in said pump chamber, shafts supporting said gears, and means biased to hold said rotary valve member in contact with the member in which said openings are formed, a check valve positioned on the discharge side of said pump and comprising a member and a seat therefor, a part on said valve shaft shaped and dimensioned in one position of adjustment to extend inwardly beyond said seat and to raise said valve member.

13. In combination in a housing member, said housing member shaped to define a low and a high pressure passage, a check valve positioned to control the passage of high pressure fluid outwardly through said high pressure passage, said housing being shaped to provide a communication between said high and said low pressure passages, said communication including a plurality of openings, a rotary valve member positioned to control said openings, a shaft for said rotary valve member, a part on said shaft adapted in one position to raise said check valve from its seat.

14. In combination in a housing member having a high and low pressure passage therein, a check valve having a movable member and positioned to control the passage of high pressure fluid outwardly through said high passage, said housing being shaped to provide a communication between said high and said low pressure passages, said communication including an opening, a rotary valve member positioned to control said opening, a shaft for said rotary valve member, a check valve-opening member associated with said shaft and adapted on rotation of said shaft to contact said movable check valve member and to open said check valve.

15. In combination in a housing member, said housing member shaped to define a low and high pressure passage, a check valve positioned to control the passage of high pressure fluid outwardly through said high pressure passage, said housing being shaped to provide a communication between said high and said low pressure passages, said communication including an opening, a rotary valve member positioned to control said opening, a shaft for said rotary valve member, a part on

said shaft adapted in one position to raise said check valve from its seat and to penetrate inwardly beyond its seat.

16. In combination in a housing member, 5 said housing member shaped to define a low and a high pressure passage, a check valve positioned to control the passage of high pressure fluid outwardly through said high pressure passage, said housing being shaped to provide a communication between said high and said low pressure passages, said communication including a plurality of openings, a rotary valve member positioned to control said openings, a shaft for said rotary valve member, a part on said shaft adapted in one position to raise said check valve from its seat, and means associated with said housing and with said shaft to hold said rotary valve member in contact with the member in which said openings are formed.

17. In combination in a housing member usable 20 in pumps and the like, said housing being shaped to define a low and a high pressure passage, the combination therewith of additional passage means positioned to place said high and low pressure passages in communication one with the other, a shaft rotatably mounted in said housing, a rotary valve member rotatable with said shaft and having a portion rotatable into position to close said additional passage, and positioning 25 means associated with said housing in said shaft for preventing linear movement of said shaft and rotary member while permitting rotation thereof.

18. In combination in a pump, a main housing member, said housing member being shaped to define a pumping chamber, a low and a high pressure passage communicating with said pump chamber, said pump housing being shaped to provide a communication between said high and said low pressure passages, a rotary valve member positioned for rotation in said housing to control said communication, a shaft for said rotary valve member, positioning means for preventing linear movement of said shaft and valve member during said rotation, closure means for closing 40 said housing member, a pair of meshing gears positioned in said pump chamber, and shafts supporting said gears, said shafts extending through and outwardly beyond the outer face of a closure means.

19. In combination in a pump, a main housing member, said housing member shaped to define a pumping chamber, a low and a high pressure passage communicating with said pump chamber, said pump housing being shaped to provide a communication between said high and said low pressure passages, said communication including a plurality of openings, a rotary valve member mounted in said housing for rotational, non-linear movement therein, to control said openings, a shaft for said rotary valve member, closure means for closing said housing member, a pair of meshing gears positioned in said pump chamber, a shaft supporting each of said gears, each of said shafts extending through said closure means, and means adapted to hold said rotary valve member in contact with the member in which said openings are formed.

20. In combination, a housing for pumps and the like, said housing being shaped to provide an inlet and an outlet passage, a by-pass positioned to bypass fluid between said passages, said bypass including a fixed ported member having a face portion surrounding the port therein, a rotary shaft in said housing, a valve member having a face conforming to said face of said ported member and carried by said shaft in con-

15

tact therewith, said valve member having portions dimensioned to cover and uncover the port in said ported member as said valve member is rotated, and positioning means associated with said shaft and housing for holding said valve member in contact with said ported member during and at all positions of rotation of said valve member.
